UNITED STATES PATENT OFFICE

130,780

DESIGN FOR A COMBINED PORTABLE TOILET SEAT AND BOWL STERILIZER

Manuel M. Shapiro, Beverly Hills, Calif.

Application September 25, 1941, Serial No. 103,476

Term of patent 3½ years

To all whom it may concern:

Be it known that I, Manuel M. Shapiro, a citizen of the United States and resident of Beverly Hills, in the county of Los Angeles and State of California, have invented a new, original, and ornamental Design for a Combined Portable Toilet Seat and Bowl Sterilizer, of which the following is a specification, reference being had to the accompanying drawing, forming part thereof, in which:

Figure 1 is a top perspective view of a combined portable toilet seat and bowl sterilizer showing my new design; and

Fig. 2 is a bottom perspective view thereof.

I claim:

The ornamental design for a combined portable toilet seat and bowl sterilizer, substantially as shown.

MANUEL M. SHAPIRO.
